(57) **CLAIM**

The ornamental design for a removable cover for data processing equipment as shown and described.

DESCRIPTION

1. Removable cover for data processing equipment

1.1 : Perspective

1.2 : Perspective

1.3 : Bottom

1.4 : Top

1.5 : Front

The claimed design for a removable cover for data processing equipment, as set forth in the following specification; FIG. 1.1 is an elevated front perspective view of a removable cover showing the new design in an illustrative use-case scenario disposed over an electronic data processing device; FIG. 1.2 is an elevated bottom perspective view, FIG. 1.3 is a bottom plan view, FIG. 1.4 is a top plan view, and FIG. 1.5 is a side elevation view (the other side being a mirror image thereof) of the electronic device cover of FIG. 1.1; the claimed ornamental design is shown embodied on an assembly that may be used, for example, as a unitary cover for at least a data processing device; in an illustrative example, the claimed ornamental design may operate as a radio permisive impact absorbing cover in a processing plant; the claimed ornamental design may, for example, be configured

(Continued)

to be disposed over a device to provide a fluidly sealing enclosure about the device, such as when the device is mounted; broken lines seen in the drawings depict unclaimed environment and form no part of the claimed design.

1 Claim, 5 Drawing Sheets
